UNITED STATES PATENT OFFICE.

JOHN MURRAY, OF LONDON, ENGLAND.

AUTOMATIC STACK-FEED.

1,395,862.

Specification of Letters Patent.

Patented Nov. 1, 1921.

Application filed December 27, 1920. Serial No. 433,523.

To all whom it may concern:

Be it known that I, JOHN MURRAY, a subject of the King of Great Britain and Ireland, and a resident of Hatton Garden, E. C., 5 London, England, engineer, have invented certain new and useful Improvements in Automatic Stack-Feed, of which the following is the specification.

The invention relates to machines in which 10 book-signatures, book-covers, sheets and like objects are fed thereto in the form of a pile, and has for its object to provide automatic mechanism for effecting this feed and for regulating the pressure of the objects in the 15 pile.

It is usually essential in the type of machine hereinbefore referred to that the object to be treated in the machine should not be presented thereto, either too loosely or 20 with too great pressure. According to the invention means are associated with the feeding mechanism for automatically adjusting the rate of feed to the demands made by the machine to which the objects are being fed, 25 thereby maintaining correct pressure of presentation.

Feeding mechanism made according to the invention comprises essentially a conveyer adapted to advance the objects in a pile toward the machine in which they are to be treated, and a finger (or fingers) bearing upon the foremost signature in the pile and adapted to regulate the rate of feed of the conveyer in accordance with the pressure exerted by the pile on the finger. The conveyer may be driven through any convenient gearing at a normal speed either less than or greater than what is actually necessary. In each case the finger bearing on the foremost 35 signature controls either directly or through a mechanical relay clutch, ratchet or equivalent mechanism in the driving gear to increase or decrease the rate of feed of the conveyer in accordance with the pressure on the 40 pile. If the objects be too loose the finger sinks into the surface of the pile and operates the clutch or equivalent mechanism to increase the feed, and when a certain pressure is attained the finger is repositioned and 45 simultaneously the speed returned to normal.

An example illustrative of one method of carrying out the invention is shown on two accompanying sheets of explanatory drawings, Figs. 1 and 2, Sheet 1, being side elevations of the feeding mechanism and Fig. 3 55 Sheet 2, an end elevation thereof.

In this example the objects A to be treated

are fed forward in a horizontal pile by conveyer chains (not shown) between register preserving devices (not shown). The drive 60 for the conveyer chains is obtained from a spur wheel B loosely mounted upon a shaft C and continuously driven through an intermediate toothed wheel B¹ from a cam shaft D. Mounted on the wheel B is a pawl B² 65 adapted to be thrown into and out of engagement with a ratchet wheel E automatically in accordance with the amount of feed required. The ratchet wheel E is interconnected with the shaft C carrying the sprockets for the conveyer chains through an epicyclic train of usual form. The train consists of a sleeved extension E¹ on the ratchet, carrying a spider in which are located bearings 70 for the planetary wheels E², E³. The wheels E³ mesh with the stationary pinion E⁴, while the wheels E² engage a pinion C¹ fast on the final motion or slow speed shaft C driving the conveyer chains. The pawl B² is provided with a toothed arc in mesh with a 80 toothed quadrant B³ forming a lever centrally fulcrumed on the wheel B and bearing a small roller B⁴ at its end remote from the quadrant teeth. The quadrant B³ is limited in travel by a pin B⁵ attached to the 85 quadrant and passing through an arcuate slot B⁶ in the wheel B. The quadrant and pawl are maintained stable in both the "on" and the "off" position by a spring B⁷ in tension between a fixed point B⁸ on the wheel B 90 and one end of the pin B⁵. It will be seen that the spring acts on opposite sides of the fulcrum according as the pawl is in, or out of engagement with the ratchet. Adjustably secured to a fixed frame F is a ramp F¹ 95 located in the circular path of the roller B⁴ when the pawl is out of engagement, but clear of the roller when the ratchet is engaged. Pivoted on the framing is a bell crank lever G one arm of which is located in 100 the path of a projecting finger B⁹ on the pawl B² when the latter is in engagement with the ratchet, but clear of the finger when the ratchet is disengaged. The wheel B rotating continuously in the direction indicated by the arrow heads in Figs. 1 and 2 carries the roller B⁴ against the stationary ramp F¹ which throws the feed pawl into engagement with the teeth of the ratchet; this position being that shown in dotted lines in Fig. 110 2. The ratchet wheel is then driven forward and with it the conveyer chains until the finger B⁹ is intercepted by the lever G and the pawl again thrown out of engagement,

causing an interruption in the feed until the ramp is again reached. Thus the conveyer chains are being advanced only while the wheel B is describing that portion of its revolution located between the ramp F¹ and the lever G. The position of the ramp on the frame F is adjustable in a circular arc to vary the duration of engagement of the pawl. The feed transmitted to the conveyer chains by this period of engagement is such that for each revolution of the cam shaft D the chains are advanced through a distance slightly less than the thickness of each of the objects A. Trip mechanism is introduced to 10 increased the normal feed of the chains automatically in accordance with the requirements called for by the rate at which the machine to which the objects A are being fed operates. The trip mechanism comprises 15 means for withdrawing the lever G out of the path of the pawl finger B⁰ which then continues to make engagement with the ratchet and consequently drives forward the conveyer chains until such time as the automatic means rethrows the lever G into the 20 position in which it interrupts the feed. The objects A are fed forward by the chains on to a plate H where they are pressed against 25 spring fingers J the lower portions of which are of comparatively small area and make 30 contact with the foremost objects in the pile. The fingers J are secured at or near the fulcrum of a bell crank lever J¹ pivoted on a transverse axis J² in brackets J³ in 35 the feeder frame. A horizontal connecting rod J⁴ makes operative connection between the depending arm of the lever J¹ and the vertical arm of the trip lever G. On the opposite side of the lever G from 40 the connecting rod, and colinear with the latter, is a spring J⁵ in tension between the vertical arm of the lever G and a point some distance to the right thereof. To the outer end of the horizontal arm of the bell crank 45 lever J¹ is secured a pin J⁶ located in a vertical slot J⁷ in the upper end of a vertical rod J⁸ the lower end of which is operatively connected to a cam lever J⁹. The lever J⁹ is fulcrumed at K and carries a tappet roller 50 engaging a cam on the cam shaft D, contact between roller and cam being maintained by a spring J¹⁰ in tension. The mode of operation of the automatic feed control is as follows:—When the foremost object in the pile 55 is about to be withdrawn by the machine to which they are fed, the lever J⁹ is lowered by its cam and the bell crank lever J¹ thus operated to remove the pressure regulating fingers J from contact with the pile. On complete withdrawal of the object, the fingers J are again brought into contact with the pile by the succeeding upward movement of the rod J⁸ caused by the continual rotation of the cam. It will be seen that as the movement of the fingers is away from the pile, the

consequent movement of the connecting rod J⁴ is in the same direction and does not remove the trip lever G from the path of the pawl finger B⁰. As already explained, the normal feed of the chains corresponding to each revolution of the cam shaft D is less than the thickness of each object. As the latter are withdrawn therefore, the pressure transmitted by the pile to the fingers J will gradually diminish until the spring J⁵ acting on the rod J⁴ will be able to pull the fingers J into the face of the pile, and the consequent movement of the rod J⁴ will be sufficient to withdraw the trip lever G from the path of the pawl finger. The ratchet 70 wheel and consequently the conveyer chains will be driven without interruption until the pressure on the fingers J has increased sufficiently to reposition the lever G in the path of the feed pawl, when the feed will again be reduced to normal. In this way the feed is automatically adjusted in accordance with the rate at which the objects are withdrawn, thus maintaining at all times a correct pressure on the pile and reducing the liability of 85 fouling to a minimum. 90

What I claim is:—

1. An automatic stack feed, comprising means for advancing the stack on each withdrawal therefrom, but at a rate normally below that required to maintain delivery, a member bearing against the face of the stack and means controlled by the position of said member for increasing the rate of feed of the stack. 95

2. An automatic stack feed, comprising means for advancing the stack on each withdrawal therefrom, but at a rate normally below that required to maintain delivery, a member bearing against the face of the stack and means controlled by the position of said member for increasing the rate of feed of the stack and for returning the stack feed to its normal rate after the stack has reached predetermined position. 105

3. An automatic stack feed comprising means for intermittently advancing the stack on each withdrawal therefrom, but at a rate normally below that required to maintain delivery, a member bearing against the face of the stack and means associated with said member for preventing the normal interruption of the stack feed and thereby increasing the rate of feed. 115

4. An automatic stack feed comprising means for intermittently advancing the stack at a rate normally below that required to maintain delivery, a member bearing against the face of the stack and means associated with said member for preventing the normal interruption of the stack feed and thereby increasing the rate of feed and for returning said feed to its normal intermittent advance of the stack after the latter has reached predetermined position. 120

5. An automatic stack feed comprising a rotary driving member, an interruptable drive connection therewith for advancing the stack, means for automatically interrupting said drive connection periodically to insure the advance of the stack at a rate of feed normally less than that required to maintain delivery, and means governed by the position of the stack for preventing the interruption of the drive to permit the advance of the stack at a rate above normal.

6. An automatic stack feed comprising a rotary driving member, an interruptable drive connection therewith for advancing the stack, means for automatically interrupting said drive connection periodically to insure the advance of the stack at a rate of feed normally less than that required to maintain delivery, and means governed by the position of the stack for preventing the interruption of the drive to permit the advance of the stack at a rate above normal and for again securing an interrupted drive at lower speed when the stack has reached 25 predetermined position.

7. An automatic stack feed comprising a continuously rotated driving member, a feed ratchet, a pawl on said driving member adapted to be thrown into and out of engagement with the feed ratchet, a toothed quadrant pivotally mounted on the driving member, a toothed arc on the feed ratchet meshing therewith, a stationary ramp adapted by engagement with the quadrant 30 to throw the pawl into gear with the ratchet, a trip finger adapted by engagement with the feed pawl to throw the latter out of gear with the ratchet, means for stabilizing the pawl in both engaged and disengaged positions, and means operated by the position of the stack for withdrawing the trip finger from the path of the feed pawl.

8. An automatic stack feed comprising a continuously rotated driving member, a feed ratchet, a pawl on said driving member adapted to be thrown into and out of engagement with the feed ratchet, a toothed quadrant pivotally mounted on the driving member, a toothed arc on the feed ratchet meshing therewith, a stationary ramp adapted by engagement with the quadrant to throw the pawl into gear with the ratchet, a trip finger adapted by engagement with the feed pawl to throw the latter out of gear with the ratchet, means for stabilizing the pawl in both engaged and disengaged positions, and a member engaging the face of the stack and operatively connected with the trip finger to maintain 50 the latter normally in the path of the feed pawl.

9. An automatic stack feed comprising a continuously rotated driving member, a feed ratchet, a pawl on said driving member adapted to be thrown into and out of

engagement with the feed ratchet, a toothed quadrant pivotally mounted on the driving member, a toothed arc on the feed ratchet meshing therewith, a stationary ramp adapted by engagement with the quadrant 70 to throw the pawl into gear with the ratchet, a trip finger adapted by engagement with the feed pawl to throw the latter out of gear with the ratchet, means for stabilizing the pawl in both engaged and 75 disengaged positions, and a member engaging the face of the stack and operatively connected with the trip finger to maintain the latter normally in the path of the feed pawl together with spring means tending 80 constantly to move said trip finger out of the path of the feed pawl.

10. An automatic stack feed comprising a continuously rotated driving member, a feed ratchet, a pawl on said driving member adapted to be thrown into and out of engagement with the feed ratchet, a toothed quadrant pivotally mounted on the driving member, a toothed arc on the feed ratchet meshing therewith, a stationary ramp 90 adapted by engagement with the quadrant to throw the pawl into gear with the ratchet, a trip finger adapted by engagement with the feed pawl to throw the latter out of gear with the ratchet, means for 95 stabilizing the pawl in both engaged and disengaged positions, and a member engaging the face of the stack and operatively connected with the trip finger to maintain the latter normally in the path of the feed pawl together with means for releasing the engagement of said member with the face of the stack when delivery therefrom is about to be made.

11. An automatic stack feed comprising 105 a continuously rotated driving member, a feed ratchet, a pawl on said driving member adapted to be thrown into and out of engagement with the feed ratchet, a toothed quadrant pivotally mounted on the driving 110 member, a toothed arc on the feed ratchet meshing therewith, a stationary ramp adapted by engagement with the quadrant to throw the pawl into gear with the ratchet, a trip finger adapted by engagement with the feed pawl to throw the latter out of gear with the ratchet, means for stabilizing the pawl in both engaged and 115 disengaged positions, and a member engaging the face of the stack and operatively connected with the trip finger to maintain the latter normally in the path of the feed pawl together with means operating with lost motion for releasing the engagement of said member with the face of the stack 120 when delivery therefrom is about to be made.

In testimony whereof I have signed my name to this specification.

JOHN MURRAY.
